TOOL

Elmer Anderson and Frank Schabert, San Francisco, Calif.; said Anderson assignor to said Schabert

Application March 28, 1932. Serial No. 601,514

7 Claims. (Cl. 254—133)

Our invention relates to a tool, and particularly to a tool for removing a bridge between studding.

It is among the objects of our invention to provide a tool which will readily remove an inaccessible bridge in the walls of a building.

Further objects of our invention include the provision, in a tool of the character described, of simple means for positively holding the tool in a selective position between the studding, and of means operable from a distance for actuating the tool to drive a bridge from its nailed position and for releasing the tool from its operating position after the bridge has been removed.

Our invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a vertical sectional view of the tool embodying our invention, taken in a plane midway between the sides of the tool housing; portions of the holding arm and actuating screw being omitted to conserve space in the drawing.

Figure 2 is a rear end elevational view of the tool.

Figure 3 is a side elevational view showing the tool positioned between the studding of a building prior to removing a bridge; and

Figure 4 is a similar view showing the tool after the bridge is removed.

In terms of broad inclusion, the tool embodying our invention comprises a frame or housing adapted for placement between the studs of a building, and releasable means engageable with the studding for holding the housing in a selected position. A driving head is mounted on the housing and is adapted for movement against a bridge between the studding, and means are provided for moving the driving head to force the bridge out of position.

In greater detail, the tool embodying our invention comprises a housing 2 adapted for placement between the studs 3 adjacent a bridge 4 to be removed. Releasable means are provided on the housing for engaging the studding to hold the tool in a selected position. For this purpose suitable claws 6 are preferably provided at the base of the housing for engaging one of the studs, and a holding arm 7 is preferably pivoted adjacent the upper end of the housing and arranged to ex-

tend across to the opposite stud. The arm 7 is preferably provided with a suitable claw 8, and the length of the arm is such that it extends upwardly and at an angle from the housing 2 when the tool is in the operating position. This arrangement is best shown in Figures 3 and 4.

A driving head is mounted on the housing 2 and is positioned for movement into engagement with the bridge 4. This driving head is preferably in the nature of an arm 9 pivotally mounted in the housing on a suitable cross-pin 11. Means are provided for moving the driving head or arm 9 against the bridge to force the same out of its nailed position. For this purpose a screw 12 is preferably provided and is threaded into a suitable nut 13 formed in the housing. The inner end of the screw is journaled in a block 14 slidably arranged in the housing on suitable guide ways 16, and the block in turn is pivotally connected to the driving arm 9 through a link 17 mounted on the pins 18.

By this mechanism it is apparent that a rotation of the screw 12 will effect a sliding of the block 14 to move the driving arm 9. A rotation of the actuating screw in one direction extends the block 14 to effect an outward swing of the driving arm, while rotation in the opposite direction retracts the block to effect an inward swing of the arm.

Since the tool embodying our invention is designed for removing bridges from inaccessible positions between the walls of a building, means are provided for operating the screw 12 from a distance. For this purpose a plurality of pipe sections 19 are preferably provided; a suitable coupling 21 being provided for detachably connecting the sections together. The lower pipe section is suitably connected to the actuating screw 12, and the upper section is adapted for receiving a hand wheel or handle-bar 22. The detaching of these elements may conveniently be effected by the removal of suitable pins 23. This extension handle arrangement adapts the tool for being lowered to any desirable position between the studs 3.

When the housing 2 is lowered along one of the studs 3 the holding arm 7 follows down, with its claw 8 sliding along the opposite stud. When the tool is finally in position against the bridge 4 to be removed, the handle-bar 22 is mounted on the upper pipe section 19 and the actuating screw 12 rotated. This forces the driving head or arm 9 against the bridge 4 and tends to shift the housing backwardly. This latter movement however is resisted by the holding arm 7 which digs its

100

105

110

claw 8 into one of the studs and simultaneously forces the claws 6 of the housing into the opposite stud. Continued turning of the actuating screw operates to drive the bridge 4 out of its nailed position, as shown in Figure 4.

5 After the bridge has been dislodged the tool is ready to be retracted. In order to do this, a flexible jerk line 26 is provided, and is suitably secured adjacent the outer end of the holding arm.

10 7. A jerk on this line unseats the arm 7, and a constant tension on the line holds the arm away from the stud as shown by the dotted lines in Figure 4. In this condition a tool may be withdrawn by pulling up on the pipe sections 19.

15 When the overhead space is limited, as is usually the case, the extension sections 19 of the handle may be disconnected as the tool is withdrawn.

The tool embodying our invention is useful in connection with the work of plumbers, electricians, and others who install equipment in the walls of a finished building. The tool is compact in structure and simple yet fool-proof in operation. We have found that the tool is a great time saver over the old methods of dropping a 25 window weight or some other heavy object between the studs to remove an inaccessible bridge.

We claim:

1. A tool for removing an inaccessible bridge between studding in a partition without breaking the walls of said partition comprising a frame 30 adapted for insertion in the partition from an end thereof and for placement between the studding adjacent the bridge, releasable means engageable with the studding for holding the frame in a selected position, a driving head mounted on the frame and adapted for movement against the bridge, means for moving said driving head, and an extensible handle adapted to extend from the operating position of the frame to the end of the partition for actuating said head moving means.

2. A tool for removing an inaccessible bridge between studding in a partition without breaking the walls of said partition comprising a housing 45 adapted for insertion in the partition from an end thereof and for placement between the studding adjacent the bridge, releasable means engageable with the studding for holding the housing in a selected position, a driving head mounted on the housing and adapted for movement against the bridge, screw means for moving said driving head, and an extensible handle adapted to extend from the operating position of the frame to the end of the partition for rotating 50 said head moving means.

3. A tool for removing a bridge between studding comprising a housing adapted for placement between the studding, releasable means engageable with the studding for holding the housing in a selected position, a driving arm pivotally mounted on the housing and adapted for movement against the bridge, and means for moving said driving arm.

4. A tool for removing a bridge between studding comprising a housing adapted for placement between the studding, releasable means engageable with the studding for holding the housing in a selected position, a driving arm pivotally mounted on the housing and adapted for movement against the bridge, a block 80 slidable in the housing, a link pivotally connecting the arm with said block, and means for moving the block.

5. A tool for removing a bridge between studding comprising a housing adapted for placement between the studding, releasable means engageable with the studding for holding the housing in a selected position, a driving arm pivotally mounted on the housing and adapted for movement against the bridge, a block 95 slidable in the housing, a link pivotally connecting the arm with said block, and an operating screw threaded in the housing and bearing against the block.

6. A tool for removing a bridge between studding comprising a housing adapted for placement between the studding, claws arranged on the base of the housing for engaging one of the studs, a holding arm pivoted adjacent the upper end of the housing and having a claw at the outer 10 end thereof for engaging the opposite stud to hold the housing in a selected position, a driving head mounted on the housing and adapted for movement against the bridge, and means for moving said driving head.

7. A tool for removing a bridge between studding comprising a housing adapted for placement between the studding, claws arranged on the base of the housing for engaging one of the studs, a holding arm pivoted adjacent the upper end of the housing and having a claw at the outer end 120 thereof for engaging the opposite stud to hold the housing in a selected position, a driving head mounted on the housing and adapted for movement against the bridge, means including a hand wheel for moving said driving head, extension means for said hand wheel, and a jerk line connected with the holding arm for releasing the housing from the studding.
